United States Patent Office

Des. 186,637
Patented Nov. 10, 1959

186,637

TELEPHONE INDEX

Julius A. Kerpel, New York, N.Y.

Application October 1, 1958, Serial No. 52,829

Term of patent 14 years

(Cl. D74—1)

Fig. 1

Fig. 2

Fig. 3

Fig. 4

Fig. 5

Figure 1 is front perspective view of a telephone index showing my new design;

Figure 2 is a front perspective view thereof, as it appears in closed position;

Figure 3 is a front elevational view as it appears with an index card in place;

Figure 4 is an end elevational view; and

Figure 5 is a rear elevational view thereof.

The essential features of the design reside in the portion shown in solid lines on the drawings.

I claim:

The ornamental design for a telephone index, substantially as shown and described.
